FISH HOLDING TABLE

Earl H. Hickey, Brogan, Oreg.

Application November 27, 1956, Serial No. 624,566

2 Claims. (Cl. 17—8)

My invention relates to improvements in tables for supporting fish for scaling or filleting.

The primary object of my invention is to provide a table for the above purpose having an attaching clamp readily and quickly attachable to the gunwale, or the like, of a boat to support the table in either inboard or outboard position relative to the boat with the table vertically adjustable on the clamp into positions most convenient for scaling or filleting of a fish thereon, by a fisherman in the boat, together with hold-down means for clamping a fish adjacent its head and tail ends to the table for scaling or filleting and which is simply constructed and easy to operate.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a view in perspective of my improved table with the clamp detached and the parts shown in position for operation to clamp a fish to the table;

Figure 2 is a view in longitudinal vertical section taken on the line 2—2 of Figure 1;

Figure 3 is a view in bottom plan;

Figure 4 is a view in vertical transverse section taken on the line 4—4 of Figure 2;

Figure 5 is a fragmentary view in plan; and,

Figure 6 is a view in vertical longitudinal section illustrating the manner in which the parts are operated to clamp a fish to the table.

Referring to the drawings by numerals, according to my invention, an oblong rectangular fish supporting table, designated generally by the numeral 1 is provided and which will now be described in detail. The table 1 comprises a U-shaped frame 3 of flat bar metal and which includes a pair of spaced side bars 5, a rear crossbar 7, and an intermediate front crossbar 9 spaced rearwardly from bifurcated front ends 11 of the side bars 5. A table top 13, of sheet metal, covers the frame 3, partly, from the rear bar 5 to the front bar 9 and is formed with downturned side and end flanges 15, 17 fitting against and suitably secured to the side bars 5 and the end bars 7, 9.

The attaching clamp, designated generally 19 comprises an elongated, inverted channel member 21 of suitable metal adapted to straddle, horizontally, the gunwale, or other part of a boat, not shown, and having a pair of clamping hand screws 23 extending through one side thereof and through bosses 25 on said side and provided with the usual hand-grip bars 27. The member 21 is provided with a pair of U-shaped upright, reinforcing flanges 29 on opposite ends thereof formed with a pair of upstanding notched detent segments 31 straddled by the front ends 11 of the side bars 5, said front ends 11 being pivoted to the segments 31 concentrically thereof by a cross shaft 33, whereby the table 1 is vertically swingably adjustable on the clamp 19.

2

The segments 31 form part of locking means for retaining the table in adjusted position. This means further includes a headed slide bolt 35 extending through the front bar 9 and flange 11 parallel with the frame 3 and provided forwardly of the table top 13 and centrally of the end bar 9 with a nut 37 carrying a detent cross rod 39 slidably extending at its ends through longitudinal slots 41 in the front ends 11 for seating in the notches 38 of the segments 31. A tension coil spring 43 on the slide bolt 35 between the nut 37 and the flange 17 of the table top 13 yieldingly urges the detent rod 39 toward the segments 31 to seat in selected notches 38 of said segments.

The hold-down means comprises a pair of inverted U-shaped clamping yokes 45 of rod material which straddle the table top 13 transversely with terminal hooks 46 extending through end apertures 47 in a pair of crossbars 49 beneath the frame 3. The crossbars 49 are slidably mounted centrally thereof on a longitudinal rod 51 extending longitudinally of and beneath the frame 3 so that by adjusting said bars 49 along the rod 51, the yokes 45 may be adjusted to straddle the head and tail end of a fish 53 disposed lengthwise on the table top 13.

A hand lever 55 is provided for pulling the rod 51 downwardly to pull the yokes 45 into clamping engagement with the fish 53 and comprises a straight handle portion 57 extending longitudinally of the table 1 beneath the rod 51. The handle portion 57 is provided with an upstanding forked front end 59 terminally pivoted, as at 61, between the bifurcated front ends 11 of the side bars 5 forwardly of the table top 13 so that said lever 55 is vertically swingable on the frame 3.

The hand lever 55 comprises a pair of side-by-side bars 63 secured together with spacing strips 65 therebetween by rivets 67. A pair of tension springs 69 are secured at one end, as at 71, to an intermediate portion of the handle portion 57 and are secured at their other ends, as at 73, to an intermediate portion of the rod 51 between the bars 49. As will be seen, the bars 49, rod 51, and springs 69 form pressure equalizing operating connections between the hand-lever 55 and the yokes 45, whereby downward swinging of the lever 55 will exert yielding uniform pressure against the yokes 45 to move said yokes downwardly into clamping position.

A locking bar 75 depends from the frame 3 between the bars 63 and the handle portion 57 in the rear of the spring 69, with an edged notch 77 engageable with a cross rivet 79 in said handle portion 57 to lock the lever 55 in downwardly swung position whereby to lock the yokes 45 in clamping position. The locking lever 75 is pivoted at its upper end, as at 81, between a pair of ears 83 on the rear bar 7 of the frame 3 for swinging of said locking bar to engage and disengage the notch 77 with the rivet 79 whereby to lock and unlock the hold-down means and the yokes 45 in locking position.

In using and operating the described invention, the attaching yoke 19 is attached, as previously explained, and the table 1 adjusted to extend from one side of the clamp 19 and then lock in level or vertically tilted position, as desired, by the described locking means. During adjustment of the table, the slide bolt 35 of the locking means is held retracted by hand to retract the detent rod 39 into idle position and when said table is properly adjusted, the slide bolt 35 is released so that the detent rod 39 will snap under the influence of the spring 43 into an appropriate notch 38 of the segments 31 to lock the table in adjusted position. The hand lever 55 is then swung upwardly into the approximate position shown in Figure 2 so that the clamping yokes 45 may be pulled upwardly for insertion of a fish 53 under the same. The fish 53 is then positioned lengthwise on the table top 13 beneath the yokes 45 and said yokes slide along the rod 51 until

they are positioned over the head and tail end of the fish as shown in Figure 6. The hand lever 55 is then swung downwardly into the position shown in Figure 6 to operate the described hold-down means for pulling the yokes 45 into clamping engagement with the fish. The locking bar 75 is then swung from the approximate position shown in Figure 2 into the position shown in Figure 6 to lock the hand lever 55 in downswung position and the yokes 45 in clamping position. Then the fish may be scaled or filleted while rigidly supported on the table top 13. Upon swinging of the locking lever into unlocking position, in a manner which will be clear, the described hold-down means will be loosened so that the yokes 45 may be lifted clear of the fish 53 for removal of the filleted or scaled fish. By reversing the position of the clamp 19, side for side, the table 1 may be positioned inside or outside a boat, as desired, that is, when attached to the gunwale or like part of a boat. Obviously, however, the clamp 19 may be attached to other parts of the boat to attach the table 1.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the invention as claimed.

What is claimed as new is as follows:

1. A table for supporting a fish for scaling or filleting comprising an elongated frame adapted to be attached to a part of a boat, a table top on said frame, a plurality of U-shaped yokes straddling said frame and top to straddle a fish on said top in laterally spaced relation and

5 downwardly movable to clamp a fish to said top, a hand lever pivoted on said frame and extending beneath the frame longitudinally thereof, a horizontal rod beneath said frame downwardly movable, means slidably connecting said yokes to said rod for adjustment laterally thereon to straddle fish of different lengths, and movement downwardly by said rod, and means operatively connecting said lever to said rod, said slidably connecting means comprising crossbars slidable on said rod, and means terminally connecting said yokes to said crossbars.

- 10 2. A table for supporting a fish for scaling or filleting comprising an elongated frame adapted to be attached to a part of a boat, a table top on said frame, a plurality of U-shaped yokes straddling said frame and top to straddle a fish on said top in laterally spaced relation and downwardly movable to clamp a fish to said top, a hand lever pivoted on said frame and extending beneath the frame longitudinally thereof, a horizontal rod beneath said frame 15 downwardly movable, means slidably connecting said yokes to said rod for adjustment laterally thereon to straddle fish of different lengths, and movement downwardly by said rod, and means operatively connecting said lever to said rod, said operating connections comprising tension springs terminally connected to said lever and rod.
